UNITED STATES PATENT OFFICE

MAX SILVERMAN AND HERMAN POMERANTZ, OF NEW YORK, N. Y.

DESIGN FOR AN EXPANSIBLE APPAREL BELT

Application filed December 31, 1931. Serial No. 42,342. Term of patent 7 years.

To all whom it may concern:

Be it known that we, MAX SILVERMAN and HERMAN POMERANTZ, both citizens of the United States, residing at New York, county and State of New York, have invented a new, original, and ornamental Design for Expansible Apparel Belts, of which the following is a specification, reference being had to the accompanying drawing, forming part thereof and in which:

Figure 1 is a plan view of an ornamental belt showing our new design.

Figure 2 is a front elevational view of the same, the entire body portion of the belt shown in dot and dash lines being formed of the same material as that indicated in full lines in Fig. 1.

We claim:

The ornamental design for an expansible apparel belt, as shown and described.

MAX SILVERMAN.
HERMAN POMERANTZ.
